WATER SKI

Erich S. Swenson, Minneapolis, Minn., assignor to The
Flour City Ornamental Iron Company, Minneapolis,
Minn., a corporation of Minnesota

Application March 7, 1957, Serial No. 45,141

Term of patent 14 years

(Cl. D71—1)

Fig. 1 is a view in top plan of a water ski showing my new design, a conventional attachment means or binding being shown by dotted lines.

Fig. 2 is a view in side elevation.

Fig. 3 is a view in rear end elevation on an enlarged scale, the attachment means being omitted for convenience of illustration;

Figs. 4, 5, 6 and 7 are enlarged transverse sections taken on the lines 4—4, 5—5, 6—6 and 7—7 respectively, the attachment means being omitted from Figures 6 and 7 for convenience of illustration;

Fig. 8 is a view in top perspective, the attachment means being omitted for convenience of illustration; and

Fig. 9 is a view in bottom plan. The dominant features of my design reside in those parts shown by full lines.

I claim:

The ornamental design for a water ski, as shown and described.
